UNITED STATES PATENT OFFICE.

WILLIAM S. GLEIM, OF LANCASTER, PENNSYLVANIA.

DESIGN FOR A TOBACCO-STOPPER.

48,861.

Specification for Design.

Patented Apr. 11, 1916.

Application filed November 30, 1915. Serial No. 64,360. Term of patent 3½ years.

To all whom it may concern:

Be it known that I, WILLIAM S. GLEIM, a citizen of the United States, residing at Lancaster, in the county of Lancaster and State of Pennsylvania, have invented a new, original, and ornamental Design for Tobacco-Stoppers, of which the following is a specification, reference being had to the accompanying drawing, forming part thereof.

The figure is a perspective view of a tobacco stopper, showing my new design.

I claim:

The ornamental design for a tobacco stopper, as shown.

WILLIAM S. GLEIM.

Witnesses:

L. C. REISNER,
GEO. ROSS ESHLEMAN.
